BOX HAVING VERTICALLY MOVABLE BOTTOM

Louis N. Sothras, Oak Park, Ill.

Application January 14, 1938, Serial No. 184,946

3 Claims. (Cl. 217—64)

This invention relates to improvements in boxes, and refers specifically to a box having a vertically movable bottom whereby merchandise such as cigars or the like, carried in said box, may be raised to the top of the box as the quantity of merchandise becomes depleted through periodic removals.

Where goods, such as cigars, candies and the like, are dispensed from containers, as the container becomes empty the merchandise is less attractively displayed. Therefore, containers have heretofore been constructed wherein the remaining goods is elevated in the container so as to present a more attractive appearance.

In boxes or containers of this type means has heretofore been provided whereby the bottom may be elevated in the box and be maintained in said elevated position. However, such means has been so constructed that the bottom can only occupy a limited number of fixed positions. Hence, in carrying goods of different sizes, different sizes of supporting means must be used.

For instance, if one of the prior art devices is utilized to contain and dispense cigars, such device is only effective when used with a box of predetermined depth containing cigars of a predetermined diameter or thickness. Obviously, where cigars of different thickness are merchandised or different depth boxes are used, the height of the devices and the dimensions of the elevational stops must be changed.

One of the objects of my invention resides in the provision of means whereby the bottom of a box may be moved and maintained at any desired elevation, said means comprising guides or ways which are substantially symmetrical throughout their length whereby they may be simply cut to fit the depth of any given box, said guides or ways engaging slidible members carried by the bottom of the box with sufficient frictional grip to permit the maintenance of said bottom at a desired elevation.

Other objects and advantages of my invention will be apparent from the accompanying drawing and following detailed description.

In the drawing, Fig. 1 is a perspective view of a box provided with the devices comprising my invention.

Fig. 2 is a sectional view taken on line 2—2 of Fig. 1.

Fig. 3 is a fragmentary sectional view taken on line 3—3 of Fig. 2.

Fig. 4 is a detailed perspective view of one of the guides comprising my invention.

Fig. 5 is a detailed perspective view of a clip

which is adapted to be slidably associated with the guide.

Referring in detail to the drawing, 1 indicates a box which may be adapted to contain cigars, candy or other similar goods. The box 1 comprises the usual sides 2 and 3, ends 4 and 5 and a cover 6 which is hingedly secured to the top edge of the side 2. A bottom 7 is positioned within the box and, as will be hereinafter more fully described, said bottom is movable in a vertical direction.

As a feature of my invention, I mount guides or ways 8 upon the inner faces of the ends 4 and 5; one guide being disposed adjacent each corner of the box. The guides 8 are preferably constructed of metal strip and are formed in two longitudinal sections, a flat section 9 and an arcuate section 10. A foot 11 is formed at the bottom of the flat section 9 and extends at right angles to the plane of said section.

The guides 8 are mounted vertically upon the ends 4 and 5 with the arcuate sections extending concave-inwardly with respect to the planes of the ends. The flat sections are disposed flush with the planes of the ends and preferably extend between the juncture of the sides 2 and 3 and the ends 4 and 5, as shown at 12 in Fig. 3. By this arrangement the guides are securely held in desired position. If desired, holes 13 may be provided in the flat section 9 for the reception of tacks 14 which assist in retaining the guides in place. However, I do not wish to be limited to any specific means for mounting the guides since the same is within the purview of any one skilled in the art. The arcuate section 10 is preferably so formed that when the flat section is disposed flush with the plane of the box end, the free edge of the arcuate sections bears, with a slight degree of tension, upon the face of the end.

A clip or slider 15 is provided for engagement with each of the guides 8, said clip being preferably constructed of metal. Each clip 15 has an outwardly extending supporting portion 16 provided with barbs or teeth 17. The opposite end of the clip is formed in a U-shape, as shown at 18 in Fig. 5. The clips 15 are adapted to be mounted upon the movable bottom 7, one clip being mounted adjacent each corner of said bottom in such position as to permit each clip to engage a guide 8. The clips are so disposed upon the bottom 7 as to permit the teeth 17 to bite into the lower face of the bottom. A hole 19 may be provided in each clip whereby a tack 20 may assist in retaining the clip upon the bottom.

To position the bottom in the box 1, the U-

shaped portions of the clips are slidably positioned in engagement with the arcuate sections of the guides. Obviously, the free edge of the guides normally bearing against the face of the ends 4 5 and 5 with a slight degree of tension, as has been hereinbefore described, will tend to confine one leg of the U-shaped portion of the clip in contact with the face of the end, and, movement of the clip parallel to the guide will be opposed by the friction thus caused.

10. To augment the frictional resistance to movement of the clips upon the guides, the normal sagitta of the arc of the arcuate section 10 is formed slightly greater than the distance between the legs of the U-shaped member. Consequently, there will be a frictional grip of the clip upon the guide at the three points indicated at 15 21, 22 and 23 in Fig. 3, due to the tendency of the U-shaped member to flatten the arcuate section 10.

20. By these provisions, although the bottom may be readily moved along the guides by exerting sufficient manual force to purposely move the same, the weight of the goods carried upon the 25 bottom will never be sufficient unaided to move the bottom downwardly. Hence, the bottom can be moved to, and be retained in any desired position within the box and is not dependent upon notches, supports of fixed length or other restricted adjustments.

30. When the bottom is in its conventional position it is supported by the feet 11 and cannot be accidentally removed from the box. When the bottom is in this position, another advantage of my invention presents itself, namely, the guide-clip arrangement resists movement to a degree in both directions; against an upwardly directed force as well as the downwardly directed

force of the weight of the goods. Consequently, said frictional resistance will tend to prevent the merchandise from being crushed when the cover 6 is closed if the bottom is accidentally jarred or bumped, which may occur, for instance, when 5 stacking the boxes.

I claim as my invention:

1. In combination with a box having a vertically movable bottom of a plurality of guides vertically disposed on the inner walls of the box, 10 a longitudinal portion of each of said guides being arcuate in cross-section, clips carried by said bottom, said clips being of U-shape, said U-shape clips embracing the arcuate portion of the guides whereby mutual pressure is exerted between said 15 clips and said guide to support said bottom at a desired elevation within said box.

2. In combination with a box having a vertically movable bottom of a plurality of guides vertically disposed on the inner walls of the box, 20 each of said guides having a free longitudinal edge which exerts resilient pressure upon the walls of the box, U-shaped clips carried by said bottom which embrace and are slidably engageable with the free edges of said guides, a 25 portion of said clips being confined between the free edges of said guides and the box to frictionally support the bottom at a desired elevation.

3. In combination with a box having a vertically movable bottom of a plurality of guides 30 vertically disposed on the inner walls of the box adjacent the corners of the box, U-shaped clips carried by said bottom which embrace and are slidably engageable with said guides, said clips contacting said guides with a sufficient degree of 35 friction to support said bottom at any desired elevation within the box.

LOUIS N. SOTHRAS.
